UNITED STATES PATENT OFFICE.

LUCILE J. BRICKEY, OF LOS ANGELES, CALIFORNIA, ASSIGNOR OF ONE-HALF TO
ALFRED C. JOHNSON, OF LOS ANGELES, CALIFORNIA.

MASSAGE ROLLER.

Application filed October 5, 1925. Serial No. 60,671.

This invention relates to improvements in massage devices.

An object of this invention is to provide an improved massage roller which can be caused to roll against the skin and which is of an improved construction having many advantages over similar devices heretofore provided.

With the foregoing and other objects in view which will be made manifest in the following detailed description and specifically provided in the appended claims, reference is had to the accompanying drawings for an illustrative embodiment of the invention, wherein:

Figure 1 is a side elevation of one form of improved massage device,

Fig. 2 is a vertical section taken through the massage device shown in Fig. 1,

Fig. 3 is an enlarged vertical section taken on the line 3—3 of Fig. 1, and

Fig. 4 is a perspective view of a massage roller of a slightly modified construction.

Referring to the accompanying drawings wherein similar reference characters designate similar parts throughout, the improved massage roller consists of an elongated roller body 10, which may be formed of wood, metal, rubber, fiber or any other desired material. Pins 11 are mounted upon the ends of the roller 10 and have heads 12 which maintain sleeves or handles 13 thereon, so that the sleeves or handles 13 can rotate on the pins. The ends of the pins 11 may be provided with screw portions 14 for securing them to the roller.

A particular feature of the invention resides in the fact that grooves or flutes 15 are formed longitudinally upon the surface 40 of the roller, defining projections or ribs 16. The grooves or flutes 15 are preferably so formed that their bottoms are wider than their tops, causing the projections or ribs 16 to appear to be dove-tailed in cross section, having their tops wider than their bottoms.

The roller is pressed against the skin and is caused to roll thereagainst. When considerable pressure is applied, the flesh tends 50 to enter the grooves or flutes 15, and if the flesh enters the grooves in any material distance, it will tend to expand therein in the enlarged or wider bottoms of the grooves.

Consequently, on moving or rolling the roller the flesh or skin on being withdrawn from the flutes or grooves tends to produce a partial vacuum therein, thus producing a suction effect on the skin and increasing the effect of the massage. It will readily be appreciated that the improved roller will effectively and very advantageously stimulate blood circulation and can be used for reducing purposes. Attention is particularly directed to the fact that the side edges of the ribs 16 are not exactly radial from the center or axis of the roller. In the preferred form of construction, the side edges of the ribs are preferably undercut, so as to be inclined slightly to radii from the center of the roller.

In the modification shown in Fig. 4 the roller 17 is similar in construction to the roller 10 and is provided with pins 18 similar to the pins 11, except that the pins 18 are much shorter. A yoke is provided as indicated at 19, in which the pins are rotatable, and this yoke carries a handle 20. It will readily be appreciated that the device shown in Fig. 4 is operable by one hand, while the device shown in Figs. 1, 2 and 3 requires the use of two hands to operate.

It will be understood that various changes in the detail of construction may be made without departing from the spirit or scope of the invention as defined by the appended claims.

I claim:

1. A massage device comprising handle means, and a roller rotatably mounted thereon, said roller having grooves or flutes formed on its exterior surface, said grooves or flutes being wider adjacent their bottoms than their tops.

2. A massage device comprising an elongated roller, and handle means for moving said roller, said roller being provided with ribs extending longitudinally of the roller, which are wider adjacent their tops than adjacent their bottoms.

3. In a massage device, a roller having ribs formed longitudinally thereof which appear to be dove-tailed in cross section.

In testimony whereof I have signed my name to this specification.

LUCILE J. BRICKEY.
